F. M. ASHLEY.

INKSTAND.

APPLICATION FILED MAR. 1, 1910.

1,093,677.

Patented Apr. 21, 1914.

UNITED STATES PATENT OFFICE.

FRANK M. ASHLEY, OF NEW YORK, N. Y.

INKSTAND.

1,093,677.

Specification of Letters Patent. Patented Apr. 21, 1914.

Application filed March 1, 1910. Serial No. 546,622.

To all whom it may concern:

Be it known that I, FRANK M. ASHLEY, a citizen of the United States, and a resident of New York city, in the county of Kings 5 and State of New York, have invented certain new and useful Improvements in Inkstands, of which the following is a specification.

My invention relates to inkstands, and the 10 object of my invention is to provide an inkstand which may be made complete in two pieces, in which the cover for the stand is made to reciprocate thereon to open and close the stand, and in which the cover is 15 provided with a depending portion which serves to act as a stop to limit the movement of the cover in either direction.

A further object of my stand is to provide means to protect the evaporation of ink 20 from the main reservoir as far as possible, and to provide a construction in which the base or body portion of the stand presents a smooth surface, so that it may be easily ground and polished on its top and side 25 surfaces.

A further object is to provide means which extend upward from the bottom of the reservoir to guide the cover.

A further object is to provide the cover 30 portion with upwardly extending projections on each side thereof which serve as a pen rack and by means of which the cover may be closed and opened when the pen is removed from said pen rack and replaced 35 thereon respectively.

Further objects and advantages of my construction will be pointed out in the following specification.

Referring to the drawings which form a 40 part of this specification, Figure 1 is a perspective view of the inkstand shown with the dip cup exposed, the dotted lines indicating a pen holder. Fig. 2 is a longitudinal sectional view taken on line $\alpha-\alpha$ of Fig. 5, showing the stand in its closed position. Fig. 3 is a cross sectional view on line $\alpha-\alpha$ of Fig. 2. Fig. 4 is a longitudinal sectional view taken on line $\alpha-\alpha$ of Fig. 5, showing the stand in its open position, and 45 Fig. 5 is a plan view of the body portion of the stand.

A indicates the body portion of the stand which I prefer to make rectangular in form substantially as shown and is made with its 50 top surface A' a plane surface. The body

portion may be cored out as illustrated in Fig. 2 at A² if desired.

The body portion is provided with a reservoir A³ and a dip cup A⁴ which are in open communication with each other by 60 reason of a passage A⁵.

A⁶ and A⁷ are projections which extend from the bottom of the stand upward to nearly the top of the body portion and inward from the front portion of the stand a 65 sufficient distance to serve as a guide for the cover.

A⁸ and A⁹ are projections which extend from the rear portion of the reservoir, therein, to assist in preventing lateral movement 70 of the cover when the cover is moved to expose the dip cup.

A¹⁰ is an inwardly projecting portion and serves as an abutment for the cover to limit its movement in opening the dip cup. 75

I prefer to form a recess A¹¹ around the top edge of the main reservoir to form a shoulder as shown, above which shoulder the ink should not rise when filling the stand. The dip cup A⁴, I prefer to extend 80 somewhat below the bottom of the main reservoir, so that all of the ink may be taken up by the pen.

The cover B is provided on each side of its top with upwardly extending portions 85 B' spaced apart from each other as illustrated to serve as a pen rack. When the pen is laid across the stand between said projections, it may be used to open and close the stand by pushing the pen holder 90 against said projections to force the cover to its open or closed position as will be readily understood, and without any appreciable loss of time so that the inkstand may be normally closed. 95

The under side of the cover is recessed, so that a very small bearing surface will rest in contact with the top of the body portion. This bearing surface is illustrated by the rib B² which extends all around the edge of the cover and by means of which the friction between the cover and body portion is reduced to a minimum. 100

Depending from the middle of the cover and formed integral therewith, is a guide portion B³ which extends nearly to the bottom of the stand and is constructed to slide in the recess A⁵ and thereby guide said cover. The rear end of said depending portion indicated by B⁴ is constructed to abut 105 110

against the projection A¹⁰ in the body portion when the front edge of the cover is open sufficiently to properly expose the dip cup A⁴, and the body portion of the stand is extended at its rear end a sufficient distance 5 to support the rear end of the cover when it is in its open position on the stand. The front end of the depending portion B³ is constructed to abut against the front wall 10 of the dip cup A⁴ when moved to cover the dip cup as illustrated in Fig. 2, so that the cover is limited in its movement in either direction when moved to open or close said dip cup, but may not be moved far enough 15 in either direction to expose the main reservoir A³.

By the construction above described, I have provided an inkstand of exceptional utility and cheapness of cost in production 20 which may be produced in cut glass at a very low cost due to the fact that the surfaces to be cut are all plane surfaces.

Having thus described my invention what I claim as new and desire to secure by Letters Patent is:

1. A two part inkstand comprising a body portion having a reservoir therein and a cover for the reservoir resting on the top of said body portion, said cover being provided with a rib having an extended surface 30 projecting within said reservoir, and projections extending upward within the reservoir for engaging said rib and guiding the cover throughout the range of its movement in either direction.

2. A two part inkstand comprising, a body portion having a flat top, a reservoir within the body portion and a guide extending from the bottom of said reservoir 40 upward nearly to the top thereof, and a low solid cover for the reservoir resting on said body portion and movable longitudinally thereof and provided with a depending portion having an extended surface adapted to coact with said guide to guide said cover longitudinally thereon, throughout its range of movement.

3. A two part inkstand comprising a body portion having an extended surface having 50 a flat top, a main reservoir within the body portion and a dip cup located at one side thereof and a restricted passage connecting said main reservoir with said dip cup, and a low cover for said reservoir and dip movable longitudinally over the reservoir and dip to cover and expose the dip, said cover having a depending portion projecting into said passage and serving to guide same longitudinally of the body portion, throughout 55 its range of movement, said depending portion being adapted to pass through the dip to abut the outer wall of the base.

4. A two part inkstand comprising a body portion the top of which presents a plane 60 surface, and having its reservoir entirely

therein, means connected to and extending upward from the bottom of the interior of said reservoir for guiding the cover, and a cover for said reservoir movable longitudinally over the reservoir resting on said plane surface and having depending means co-acting with said upwardly extending means in the reservoir to guide said cover longitudinally on said body portion.

5. A two part inkstand comprising a body 75 portion having its top formed with a plane surface and a low cover mounted and movable longitudinally thereon and having its under side recessed to form a rib at its edge and contacting with the plane surface of the body portion for the purpose set forth, and means comprising a rib having an extended surface depending from the cover within said reservoir for guiding the cover and limiting its movement in each direction.

6. A two part inkstand comprising a body portion having its top formed with a plane surface and having a reservoir therein, and a recess extending around the top of said reservoir, and a cover resting on said plane 80 surface and having a depending portion which serves as a guide therefor.

7. An inkstand comprising a body portion containing a reservoir, a cover therefor, means for guiding said cover longitudinally 95 on said body portion so as to open and close said reservoir, there being projections formed on the top of said cover so as to constitute a pen rack, said projections being so proportioned as to enable the reservoir to be 100 uncovered through the instrumentality of the penholder by the natural movement of the hand in removing a pen from the rack.

8. An inkstand comprising a body portion containing a reservoir, a cover therefor, 105 means for guiding said cover longitudinally on said body portion so as to open and close said reservoir, said cover having laterally spaced projections formed thereon, said projections having recesses formed therein and 110 located entirely above the body of the cover, permitting the operator to firmly grasp the pen and at the same time push the cover forward to open the reservoir.

9. An inkstand comprising a body portion 115 having a reservoir therein, a cover having a depending portion extending into the reservoir, a pair of guide members located within the reservoir at the forward end thereof, and a pair of guides located within the reservoir at the rear end thereof, said guides co-operating with said depending portion to guide said cover over said body portion.

10. A two part inkstand comprising a base having a reservoir therein and a reciprocating cover for the reservoir resting on top of said base, said cover being provided with a rib having an extended surface projecting from substantially midwidth thereof into the reservoir, and projections extending 120

upward within the reservoir and spaced from the lateral walls thereof for engaging said rib and guiding the cover throughout the range of its movement in either direction.

11. A two part inkstand comprising a base having an entirely flat top and provided with a reservoir therein, a reciprocating cover for the reservoir resting on the top 10 of said base, said cover being provided with a rib having an extended surface projecting within said reservoir, said rib being disposed substantially at the midwidth of the cover, and projections extending upward

within the reservoir and spaced from the 15 lateral walls thereof for engaging said rib and guiding the cover throughout its range of movement in either direction, the ends of the rib serving as stops for limiting the movement of the cover by engagement with 20 the forward and rear walls of the reservoir.

Signed at New York city in the county of New York and State of New York this 25th day of February A. D. 1910.

FRANK M. ASHLEY.
